US0D1016662S

(12) **United States Design Patent** (10) **Patent No.:** **US D1,016,662 S**
(45) **Date of Patent:** **** Mar. 5, 2024**

(54) **TREE STAND**

(71) Applicant: **David Pascual**, Murrieta, CA (US)

(72) Inventor: **David Pascual**, Murrieta, CA (US)

(**) Term: **15 Years**

(21) Appl. No.: **29/821,543**

(22) Filed: **Dec. 30, 2021**

(51) LOC (14) Cl. **06-99**

(52) U.S. Cl.

USPC **D11/130.1**
